UNITED STATES PATENT OFFICE.

ROBERT WEILENMANN, OF SCHAFFHAUSEN, SWITZERLAND.

FASTENER TO BIND LOOSE SHEETS OF PAPER.

Application filed December 8, 1926, Serial No. 153,425, and in Germany December 8, 1925.

The present invention relates to a new and improved fastener for loose sheets, letters and so on.

The main object of the invention is to provide a simple, strong and cheap device which is easily and quickly operated and which takes up but little space in the folder, file or binder in which the fastener may be mounted.

With these and other objects in view the invention consists in the particular construction of the device and of its parts which in the specification is particularly set forth.

In the accompanying drawings the preferred construction of the new device is shown by way of an example.

Fig. 1 shows part of an open folder or binder in an end view,

Fig. 2 is a top view and

Fig. 3 a side view of the fastening device of the binder, the device being shown in an inverted position.

Fig. 4 illustrates a closed binder in an end view and Fig. 5 the same part in a top view with the cover broken away.

Fig. 6 shows on a larger scale a cross-section through the fastening device and

Fig. 7 is a section view of the end portion of binding needle.

The folder or file comprises a cover 1, 2 which may be made of stiff paper, cardboard or the like. At 3 the cover 1 is provided with a double fold and to said fold a flat strip 4 of suitable metal for instance brass, steel etc. is fixed, by means of two flexible prongs or needles 5 fixed at one end to the strip and passing through said folds.

Each prong 5 comprises a coiled wire of springy material for instance steel wire and a conical head 7 fixed to the free end of said wire coil. On the prongs 5 the loose paper sheets A are assembled. The sheets are perforated in the usual manner and by well-known punching machines the holes made

being such that the prongs 5 pass freely through them. On the top of the pile of loose sheets A a sheet metal strip 8 is placed which is provided with holes through which the prongs 5 pass. On the strip 8 two bearings 9 are provided in which the centre portion 10 of a U-shaped wire grip is rotatably mounted. The shanks 11 of said grip are hollow and into the bores thereof the prongs 5 may be easily passed. The centre

portion 10 is provided with a hump 14 lying in a common plane with the shanks 11.

On the strip 8 movable between the bent-over side edges of the strip 8 a slide 12 is arranged. The slide 12 passes over the portion 10 and provided with a recess 13 in its middle raised portion, said recess being adapted to receive the hump 14 if the shanks 11 are standing upright. The slide 12 is provided with a tongue 15 forming a rest for the hand to move the slide. Between the tongue 15 and the bearing 9 a coiled spring 16 is arranged which tends to move the slide 12 over the hump 14.

To place papers in the file, the strip 8 and the parts fixed thereto are removed, when the prongs 5 assume a vertical position owing to their springy nature. The papers A are placed in the file on said prongs 5 and now the strip 8 with the grip standing vertical thereon (Fig. 1) is passed on the prongs 5 in such a manner that the prongs 5 pass through the hollow shanks 11. The strip 8 is firmly pressed on the papers 8 and to bind them the grip is turned down (Fig. 2). The slide 12 is now passed over the hump 14 (Fig. 5) the grip is locked and the fastener is now closed. To open the fastener the slide 12 is moved by hand against the action of spring 16, the grip is turned to stand upright and the slide 12 passes under the action of spring 16 upwards in Fig. 2 in such a manner that the hump 14 enters the recess 13. The grip is then held by the slide 12 in its upright position.

To conveniently remove any paper from the file the strip 8 with the grip is passed on the prongs in the inverted position shown in Fig. 3. All the papers above that one desired are now assembled on the downwardly projecting shanks 11; the pile above the desired document is not disturbed and may be placed on the lower file as a whole after the desired paper has been taken from the prongs.

Within the coiled wire 5 a short core 6 of rubber or the like is arranged near the end thereof to give the prongs 5 some stiffness and to make the insertion into the shanks easy.

What I wish to secure by U. S. Letters 105 Patent is:—

1. A fastener to bind loose sheets of paper adapted to be connected with a folder, or the like comprising in combination a strip of stiff material, two flexible prongs fixed thereto, a second strip of stiff material, and a U-shaped grip rotatably mounted on the

second said strip, and having hollow shanks adapted to receive said prongs.

2. A fastener to bind loose sheets of paper adapted to be connected with a folder, or the like comprising in combination, a strip of stiff material, two flexible prongs fixed thereto, a second strip of stiff material, a U-shaped grip rotatably mounted on the second said strip, having hollow shanks adapted to receive said prongs, a bend or hump on the centre portion of the grip, a slide on the second said strip adapted to pass over the bend of the grip when the grip lies flat on the strip, to thereby lock the grip.
- 5 3. A fastener to bind loose sheets of paper adapted to be connected with a folder, or the

like comprising in combination a strip of stiff material, two flexible prongs fixed thereto, a second strip of stiff material, a U-shaped grip rotatably mounted on the second said strip, having hollow shanks adapted to receive said prongs, a bend or hump on the centre portion of the grip, a slide on the second said strip adapted to pass over the bend of the grip when the grip lies flat on the strip and to lock the grip, said slide having a recess to receive the said bend and to secure the grip in its upright position on the strip. 20 25

In witness whereof I affix my signature.

ROBERT WEILENmann.
